Hopewell, deceased

Application January 8, 1932, Serial No. 585,416

3 Claims. (Cl. 139—187)

This invention has for its object to provide means for preventing the rebound of a filling carrier or shuttle toward the center of the loom after it has been projected or picked into the shuttle box.

The invention has for its object more particularly to provide such a means in connection with an electro-dynamic means associated with the filling carrier or shuttle for projecting it across the loom.

These and other objects and features of the invention will appear more fully from the accompanying description and drawing and will be particularly pointed out in the claims.

In the pending application of Bowles and Smith, Serial No. 530,716, filed April 16, 1931, there is disclosed an electro-dynamic means associated with a filling carrier acting to project the filling carrier across the loom and also

to check the movement of the filling carrier when it is projected into the shuttle box from the opposite side of the loom, together with a stop for limiting the movement of the filling carrier when thus projected into the shuttle box.

A preferred form of the present invention is disclosed herein in connection with a form of apparatus such as disclosed in the aforesaid application, and as the present invention has to do with but one feature of the loom, it is only necessary here to illustrate and describe those features of a preferred form of the broad construction with which the invention is particularly associated.

As the construction is the same at both sides of the loom, it is only necessary to illustrate and describe in detail the construction at one side.

In the drawing:

Fig. 1 is a top plan view of the construction at one end of the lay of a loom showing a portion of the electro-dynamic unit, a filling carrier or shuttle associated therewith in the shuttle box engaging the stop, together with a construction embodying a preferred form of the present invention shown in locking position.

Fig. 2 is a view on a larger scale taken in vertical cross section on the line 2—2 of Fig. 1.

Fig. 3 is a detail in perspective of a portion of the shuttle box.

Fig. 4 is a diagram showing the electrical circuits concerned in the operation of the loom.

The electro-dynamic mechanism herein illustrated for projecting the shuttle from the box and checking its movement when it arrives in the box is herein shown as operating on the inductive principle. The electro-dynamic means is energized by a three-phase alternating current producing a traveling field and inducing current in an electrically conductive shuttle, with the result that when the electro-dynamic

means is energized, the shuttle is projected from the box across the loom. When the shuttle is projected from the opposite side of the loom into the box, the electro-dynamic means is energized by direct current, which acts to induce current in the electrically conductive shuttle and thus to check the movement of the shuttle as it enters the field of the electro-dynamic means. In order that the shuttle may be checked accurately in the same position and may not pass out of the field of the electro-dynamic means, a stop is provided at the outer end of the shuttle box with which the shuttle engages and by which its movement is limited. The shuttle may, however, rebound upon striking such a stop and thus be mispositioned in the shuttle box or even rebound to a position toward the center of the loom more or less out of the effective field of the electro-dynamic means.

The present invention provides means for preventing this rebound of the shuttle and specifically for locking it against rebound from its position as limited by the stop. While the means for preventing rebound is particularly designed for use in connection with an electro-dynamic means for projecting and checking the movement of the shuttle, it is of broader application. The means specifically disclosed for embodying the invention is shown as an electrically controlled device or still more specifically as a solenoid, the core of which in combination with a recess in the shuttle wall acts to lock the shuttle against rebound and in which the solenoid is energized in timed relation with the electro-dynamic means to withdraw the core from engagement with the shuttle when or just before the electro-dynamic means is energized to project the shuttle from the box.

A preferred construction is illustrated at the lefthand side of the lay. The bottom of the shuttle box is shown as a race plate 1 on the lay 2, the rear wall 3 extends upward from the lay and the front wall is constituted by one of the core sections 4 of the electro-dynamic unit which comprises these core sections and the coils 5, all as fully disclosed in the aforesaid Bowles and Smith application. The shuttle 6 is shown in the shuttle box and as comprising a laterally projecting, electrically conductive metal fin 7 which extends between the core sections 4. The outer end of the shuttle box is provided with a hood 8 secured at 9 to the rear wall 3 and open at the front. This hood has mounted therein at the outer end a stop gate 10 hinged at 11 to swing inwardly but limited in its outward movement by the hood, and this stop gate is provided with layers of rawhide or suitable material 12 against which the nose of the shuttle engages when it reaches the limit of its move-

ment into the shuttle box after being projected from the opposite side of the loom.

The rear wall 13 of the shuttle is provided near each end with a recess 14 and this recess is preferably formed in a hard metal wear plate 15 inserted in the wall of the shuttle.

The solenoid is secured to the rear wall 3 of the shuttle box in position for the core of the solenoid to cooperate with the recess 14 adjacent the outer end of the shuttle. This solenoid is enclosed by a casing 16 attached at 17 to the rear wall 3. The base 18 of the casing extends through the rear wall 3 of the shuttle box. The armature 19 is mounted in the outer end of the casing and the core 20 is guided at its rear end in the armature and at its forward end in the base 18. This core at its forward end is bevelled at 21 so that as the shuttle enters the box and engages the bevelled end of the core, the core is forced backward, but when the core is in its forward position, it seats in the recess 14 engaging the outer wall thereof and thus locks or latches the shuttle against movement toward the center of the loom. The core is projected forward by a helical spring 22 seated in the base of the casing between a shoulder 23 on the core and a screw plug 24.

In the operation of this form of the invention, when the shuttle is projected into the box and nears the end of its movement, it pushes back the core of the solenoid and when the nose of the shuttle engages the stop, the core of the solenoid snaps into the recess 14 and locks the shuttle at the end of its movement against rebound. When the electro-dynamic unit is energized to project the shuttle out of the box, the solenoid is energized to withdraw the core from engagement with the recess in the shuttle, the energization of the solenoid preferably taking place slightly in advance of the energization of the electro-dynamic unit.

In Fig. 4 there is illustrated diagrammatically the mechanisms involved, together with a simple form of electrical circuits and means for controlling the supply of current to the mechanisms in proper timed relation. A three-phase alternating current is shown for energizing the electro-dynamic units at the opposite sides of the loom for projecting the shuttle from the respective boxes; a direct current for energizing the electro-dynamic units at the opposite sides of the loom for checking the movement of the shuttle when projected into the respective boxes; and the same direct current for energizing the solenoids at the opposite sides of the loom to unlock or release the shuttle when the respective electro-dynamic unit is energized by the alternating current to project the shuttle from the box. The various circuits extend to switches indicated as S1 and S2 for the solenoids at the left and right-hand sides of the loom, respectively, A1 and A2 for the control of the three-phase alternating current for the electro-dynamic units at the left and right-hand sides of the loom, respectively, and D1 and D2 for the control of the direct current for the electro-dynamic units at the left and right-hand sides of the loom, respectively. These switches are controlled in proper timed relation by cams 25 on a cam shaft 26 mounted above the switches and driven by a suitable operating element of the loom, as disclosed in the aforesaid Bowles and Smith application. The system thus disclosed in connection with Fig. 4 is, how-

ever, only for the purpose of disclosing one good means for securing the proper operation of the electro-dynamic means and the electrically controlled device, such as the solenoid, in which a simple and preferred form of the invention in its more specific aspects is embodied.

It will thus be seen that a very effective means is provided for preventing or limiting the rebound of the shuttle when projected into the box and its movement has been limited as by 10 the stop. Preferably the locking or latching means such as the solenoid core 20 and the recess 14 are so located as to prevent any rebound, but the location may be such as to limit the rebound to any desired extent depending 15 upon the relation between the distance from the core to the stop and the distance from the recess to the nose of the shuttle. The position of the cams 25 on the cam shaft also determine the exact period at which the core shall be withdrawn from the recess in the shuttle relatively 20 to the energization of the electro-dynamic means for projecting the shuttle from the box.

It is to be understood that in its broader application the invention is not limited to the particular means employed for controlling the operation of the means for preventing the rebound of the shuttle not to the association of the rebound preventing means with an electro-dynamic means for projecting and checking the filling carrier nor otherwise than as set forth in the claims.

Having thus described the invention, what is claimed as new, and desired to be secured by Letters Patent, is:

1. In a loom, a shuttle having a recess in its wall, a shuttle box, a solenoid mounted on the shuttle box with its core yieldingly forced toward the shuttle as the shuttle enters the box and acting to engage in said recess and to lock the shuttle against rebound when the shuttle is properly positioned in the box, and means acting to energize the solenoid and withdraw its core from the shuttle when the shuttle is to be projected from the box.

2. In a loom, a shuttle box, a shuttle having a recess in its wall, electro-dynamic means associated with the shuttle to project the shuttle from the box, a stop for limiting the movement of the shuttle when projected into the box, a solenoid mounted on the shuttle box with its core yieldingly forced toward the shuttle as the shuttle enters the box and acting to engage in said recess and lock the shuttle against rebound from the stop, and means acting to energize the solenoid and withdraw the core from the shuttle when or before the electro-dynamic means acts to project the shuttle from the box.

3. In a loom, a shuttle box, a shuttle having a recess in its wall, electro-dynamic means associated with the shuttle to project the shuttle from the box, a stop for limiting the movement of the shuttle when projected into the box, a solenoid mounted on the shuttle box with its core yieldingly forced toward the shuttle as the shuttle enters the box and acting to engage in said recess and lock the shuttle against rebound from the stop, and current controlling means for the electro-dynamic means and for the solenoid acting to effect the energization first of the solenoid to withdraw the core from the shuttle and then of the electro-dynamic means to project the shuttle from the box.

FRANK B. HOPEWELL.
